UNITED STATES PATENT OFFICE

HOWARD A. TRAFTON, OF BROOKLYN, NEW YORK, ASSIGNOR TO THE NESTLE-LEMUR COMPANY, OF NEW YORK, N. Y., A CORPORATION OF OHIO

DESIGN FOR A CASING FOR A HAIR-WAVING MACHINE

Application filed March 14, 1931. Serial No. 39,094. Term of patent 7 years.

To all whom it may concern:

Be it known that I, HOWARD A. TRAFTON, a citizen of the United States, residing at Brooklyn, in the county of Kings and State of New York, have invented a new, original, and ornamental Design for Casing for a Hair-Waving Machine, of which the following is a specification, reference being had to the accompanying drawings, forming part thereof.

In the drawings—

Figure 1 is a perspective view of a casing for a hair-waving machine, showing my new design; and

Figure 2 is a top plan view thereof.

I claim:

The ornamental design for a casing for a hair-waving machine, as shown.

HOWARD A. TRAFTON.
